ABSTRACT OF THE DISCLOSURE

In a conductor spacer for multi-conductor electrical overhead transmission lines having a conductor clamp composed of two jaw parts hinged together and connected to a spacer frame by a flexible joint, a single means serves to draw the jaw parts together to clamp a conductor between the jaw parts and to connect the clamp to the flexible joint.

This invention relates to conductor spacers for electrical overhead transmission lines and concerns such spacers which will accommodate relative longitudinal movements of the conductors spaced by the spacer.

According to this invention, a conductor spacer for multi-conductor electrical overhead transmission lines comprises a spacer bar or frame to hold at least a pair of conductors apart and a pair of clamps one to grip each of said conductors which are to be held apart, each clamp comprising two jaw parts hinged together and means capable of engaging and disengaging at least one of the jaw parts for drawing the jaw parts together to grip a conductor between the jaw parts, said means also serving to attach the clamp to a flexible joint connecting the clamp to the spacer bar or the spacer frame.

Preferably the flexible joint comprises a rubber bush which, by deformation, accommodates relative hinging movements of the clamp and the spacer bar or frame, the bush having an inner rigid sleeve part with a threaded bore receiving a screw bolt, the bolt and the sleeve part serving to draw the jaw parts together and to attach the clamp to the flexible joint.

In the preferred form, said sleeve part is fixed to the other of the clamp jaw parts and the bolt engages said one of the clamp jaw parts.

Preferably, also the screw bolt carries a swing washer of elongated form, and said one of the clamp jaws has a fork the limbs of which are bridged by the washer to engage the fork with the bolt, the washer being rotatable through 90° upon loosening the bolt, to disengage the fork.

Specific embodiments of the present invention will now be described by way of example, with reference to the accompanying drawings in which:

FIG. 1 is a cross-section of a conductor clamp for a conductor spacer according to this invention,

FIG. 2 is a view in the direction of arrow 2 in FIG. 1,

FIG. 3 is a side elevation of a twin conductor spacer employing conductor clamps as shown in FIGS. 1 and 2, and

FIG. 4 is a side elevation of a quadruple conductor spacer employing conductor clamps as shown in FIGS. 1 and 2.

Referring to FIGS. 1 and 2, each conductor clamp comprises two jaw parts 10, 11 hinged together as at 12 by means of a hinge pin 13. The clamp is shown in its operative position clamped about a conductor 14. Part of a spacer bar or spacer frame is indicated at 16. The hinge pin lies close to the conductor on the opposite side

2

of the conductor from the spacer bar or spacer frame, that is to say to the outside of the conductor bundle of which the conductor forms a part and the jaw parts extend from the hinge pin, inwardly of the bundle, respectively over and under the conductor as viewed in FIG. 1 towards the spacer bar or spacer frame. Screw means, hereinafter described, is provided to draw the inner ends of the jaw parts together to clamp the conductor 14 between the jaw parts 10, 11. The clamp accordingly encloses the conductor and by virtue of the relative transverse position of the conductor with respect to the hinge pin 13 and the clamping screw 29 the clamp is able to take an effective grip on the conductor, the clamp offering a good mechanical advantage.

The clamp is connected to the part 16 by means of a flexible joint 19 comprising a cylindrical rubber bush 20. The bush is housed in an eye 21 on the part 16 and may be adhesively united with the inner, cylindrical surface of the eye. The bush 20, which may alternatively be spherical, has an inner, cylindrical, metal part 24 which may be bonded to the rubber of the bush. The part 24 is riveted at one end, as at 26, to the lower clamp jaw part 10 and is provided in its other end with a blind, screw threaded bore 28 which receives the clamping screw 29 which takes the form of a screw bolt.

The screw bolt 29 carries a swing washer 30 which is of elongated rectangular form with rounded ends in plan, as shown in FIG. 2, and of T-shape in the plane through the screw bolt axis parallel with its longer sides so as to 30 present a central portion 30a of generally square outline to fit between interfacing surfaces 32a of fork limbs 32 on the inner end of the upper jaw part 11, and wing portions 30b to overlie recessed step surfaces 32b on the fork limbs, as shown in FIG. 2. The under surface of the 35 wing portions 30b and the step surfaces 32b may be correspondingly curved as indicated in FIG. 1 about a common axis parallel with the axis of the conductor 14.

This allows the washer 30 to tilt on the step surfaces to accommodate relative angular movements of the clamp 40 jaw parts 10 and 11 during tightening and untightening the screw bolt 29.

In FIGS. 1 and 2 the clamp is shown gripping the conductor 14 in the installed condition of the spacer. The wing portions 30b of the washer 30 are seated in the recesses in the fork limbs 32, the washer bridging the fork limbs 32 to engage the screw bolt with the fork. In this position the washer is prevented from rotating on the screw bolt. When the screw bolt is loosened sufficiently without disengaging the part 24, the washer is freed for rotation through 90° to align the washer with the gap 35 between the fork limbs. The washer is of a size to pass through the gap 35 when aligned with the gap. The jaw part 11 is accordingly free to swing upwardly to release the conductor from the clamp.

The screw bolt remains screwed into the bore 28 of the part 24 and the washer 30 remains captive on the screw bolt. When the cable spacer is installed, the reverse procedure is adopted. Installation is carried out from a cradle running on the conductors. The construction of clamp with no separate parts to be assembled, ensures that parts cannot be dropped and lost.

The form of clamp illustrated presents a smoothly curved profile without protuberances, edges or points 65 which are likely to give rise to corona discharge. A good electrical performance is thus obtained.

The rubber bush 20 accommodates relative angular movements of the conductor 14 and the spacer frame so that relative longitudinal movements of the conductors spaced by the spacer and relative movements of the conductors in a plane normal to the plane of the conductors,

is permitted. The rubber bush may insulate the clamp electrically from the spacer frame.

The rubber bushes assist in damping out low amplitude vibrations of the conductors and prevent or reduce the transmission of vibrations through the spacer from one conductor to another.

A twin conductor spacer, according to the invention using clamps and flexible joints as described with reference to FIGS. 1 and 2 is shown in FIG. 3. Two clamps are employed, one for each of the conductors 14, the 10 clamps being carried one on each end of a straight spacer bar 16, by flexible joints indicated at 19.

FIG. 4 illustrates the use of the clamps and flexible joints in a quadruple conductor spacer according to the invention. The clamps are carried one at each of the four 15 corners of a rectangular spacer frame 60 and connected thereto each by a flexible joint 19 as previously described.

The spacer of FIG. 4 may be modified to incorporate a triangular spacer frame, not shown, carrying three of the clamps as previously described, one at each corner 20 of the triangular frame and each connected to the frame by a flexible joint 19 as previously described.

The spacer frame 60 of FIG. 4 may be of any other convenient shape. It may for example be formed by radiating arms there being as many arms, as there are conductors 14 in a bundle of conductors to be spaced. For four conductors, an H frame may be employed. The frames need not necessarily be rigid frames. The frames may be articulated frames.

Spacers according to the invention employing conductor clamps and flexible joints as described with reference to FIGS. 1 and 2 have fewer parts and are more economically produced.

I claim:

1. A conductor spacer for multi-conductor electrical 35 overhead transmission lines comprising:
a spacer bar or frame to hold at least a pair of conductors apart;
at least a pair of clamps, one clamp gripping each of said conductors which are to be held apart, each 40 clamp including:
first and second jaw parts which are hinged together, said first jaw part having a fork-like portion; and
means including a screw bolt carrying an elongated 45 swing washer, for releasably engaging the

limbs of the fork-like portion with the screw bolt for drawing the jaw parts together to grip a conductor between the jaw parts, said swing washer being rotatable upon loosening the bolt to disengage the fork-like portion; and
a flexible joint including a rubber bush connecting said engaging means to said spacer bar or frame to form a flexible connection between the clamp and the spacer bar or frame, said rubber bush having an inner, rigid sleeve part fixed to said second jaw part and having a threaded bore receiving said screw bolt, said screw bolt and said sleeve part serving to draw the jaw parts together and to attach said clamp to said flexible joint.

2. A conductor spacer as claimed in claim 1 wherein the swing washer is rotatable through 90°, upon loosening of the screw bolt, to disengage said fork-like portion.

3. A conductor spacer as claimed in claim 1 wherein the washer has a central portion to fit between interfacing surfaces of the fork limbs to prevent rotation of the washer, the washer having wing portions to overlie the fork limbs.

4. A conductor spacer as claimed in claim 3 wherein the fork limbs have recessed step surfaces to receive the wing portions of the washer.

5. A conductor spacer as claimed in claim 4 wherein the undersurfaces of the wing portions and the step surfaces are correspondingly curved about a common axis parallel with the axis of the conductors in use of the spacer.
